UNITED STATES PATENT OFFICE.

PHILIP LINDEMAYER, OF BALTIMORE, MARYLAND.

PAPER BOX.

SPECIFICATION forming part of Letters Patent No. 476,661, dated June 7, 1892.

Application filed February 11, 1892. Serial No. 421,118. (No model.)

To all whom it may concern:

Be it known that I, PHILIP LINDEMAYER, a resident of Baltimore, in the State of Maryland, have invented certain new and useful Improvements in Paper Boxes; and I do hereby declare the following to be a full, clear, and exact description of the invention, such as will enable others skilled in the art to which it pertains to make and use the same.

This invention relates to the covering or wrapping of boxes, and has for its object to provide means for applying covers or wrappers to boxes with greater accuracy, rapidity, and economy than heretofore attained; and it consists in the improvements hereinafter described and particularly pointed out.

In the accompanying drawings, Figure 1 is a plan of a flattened or partially-formed tube suitable for making three boxes and having a cover partially broken away. Figs. 2 and 3 are enlarged sections on lines xx and zz , respectively, of Fig. 1; and Fig. 4 is an enlarged section on the same plane as Fig. 3 after the flattened tube has been brought into strictly tubular form.

It is customary to make paper-board boxes from sections of a rectangular tube. The board is first marked, cut, bent, and pasted to form what may for convenience be called a "tube-blank" or "flattened tube," as indicated in Figs. 1 and 2, in which the spaces enclosed between the lines marked 1 and 2 indicate portions of a board adapted to constitute sides of a box when formed and spaces included between the lines 2, 4, and 3 indicate portions adapted to be folded at right angles to the said sides to form the ends of the boxes. The lines 4 also indicate slits in the board of which the tube is made, and the lines 3 indicate where the tube-blank is cut to separate the sections that are to be formed into boxes. Wrappers or covering-labels are usually applied to the sections after they have been opened or made to assume a tubular form by pressing the sectional tube-blank at its edges and forcing the several sides to assume an angular position with respect to each other, as indicated in Fig. 4. The wrapper, being cut to the proper size, is covered with paste upon one side and wrapped about the tube, which is generally placed upon the pasted wrapper

and turned over upon it three or four times until it adheres to the entire surface of the short tube. One end of the box is then closed by folding the slitted end portions of the board at right angles to the sides and then folding upon it the corresponding part of the wrapper, whereupon the box is filled and the other end closed in like manner. According to this customary method the wrappers are applied to the boxes singly and only after the sections of the tube-blank have been brought into strictly tubular form, as by compressing the tube-blank edgewise, as it would be impracticable to first apply the wrapper for the reason that the tube could not be formed from a tube-blank after the application to its entire surface of a pasted wrapper without injury to the latter.

Both skill and time are required to properly apply a wrapper to a single box and so that it shall not be awry, and, besides, an objectionable quantity of paste or other adhesive is necessarily employed. To avoid these objections I first provide a wrapper equal in length to the tube-blank—such as indicated in Fig. 1 of the drawings—and suitable for forming two, three, or more boxes and of such width that it will inclose the said blank circumferentially and its edges overlap, so as to permit them to be pasted together and the wrapper thereby secured upon the blank. Printed matter can, if desired, be put on the wrapper before it is thus applied to the tube-blank and so that each box, when completed, will be provided with any desired label on its sides and ends.

Preferably each portion or section of the wrapper is made to adhere to one or more sides of the box in some convenient manner, as by a small quantity of adhesive applied to the same or to the corresponding portion of the wrapper, to prevent slipping of the subsequently-formed sections of wrapper and tube with reference to each other during the final folding operation. It is important that the method of fastening shall be such as not to interfere with the formation of tubes from the tube-blank sections, as above described. The wrapper is by preference so placed upon the tube-blank that its overlapping edges or seam shall not be adjacent to the overlapping

edges of the tube-blank to avoid all danger in the completed article of leaking through the joints of both in case of accidental fault of manufacture—as, for example, if the slit 4 5 be made in any case to extend backward beyond the end of the box—that is, toward its body beyond the bending-line 2 of the end. The entire wrapper having been applied to the tube-blank is, together with said blank, 10 cut into sections on the line 3' of the former and line 3 of the latter. The covered flat tube-blank sections thus produced are compressed edgewise to form tubes, whereupon one end of each is closed, the box filled, and 15 its opposite end also closed, as before set forth.

In applying the wrapper to the tube-blank by the present method but two foldings of the wrapper are required instead of four, as formerly, and the series of connected wrappers corresponding to a considerable series of boxes can be applied as quickly or quicker than a single wrapper to a tube by the old method and with greater accuracy, first, because the corresponding lines of the wrapper 25 and flat tube-blank are longer and present a better guide to the eye than in case of a single wrapper and short tube, and, secondly, because any error which may occur in placing the long flat tube-blank and its wrapper together is distributed throughout the series 30 and is thereby made small for each box. The separate cutting of the wrapper-blank to make individual wrappers is obviated, this being effected by the same operation which cuts the 35 tube-blank into series.

I am aware that two strips of paper have been pasted together at intervals on lines corresponding to the bottoms of bags to be produced and a longitudinal edge of each strip

subsequently pasted, and that the double strip 40 thus produced has been formed into a flattened tube and then transversely severed one by one into bag-sections along the first-named pasted lines, the strips being drawn lengthwise through a strip-pasting and tube-forming 45 machine, and such mode of procedure is not of my invention.

Having thus described my invention, what I desire to secure by Letters Patent is—

1. The improvement in the art of making 50 covered boxes, which consists in slitting strips of paper at intervals lengthwise preparatory to producing the box ends, forming the tube-blank or flattened tube adapted to make several boxes, applying to said tube a wrapper, 55 simultaneously cutting said wrapper and the tube into sections across the slitted portion of the latter, changing said sections into tubular form, and closing their ends, substantially as set forth.

2. The improvement in the art of making covered boxes, which consists in forming the tube-blank or flattened tube adapted to make several boxes and in applying to said tube a 60 wrapper, securing the wrapper to parts of the tube-blank corresponding to sides of the boxes when completed, simultaneously cutting the tube and its wrapper into sections, changing said sections into tubular form, and closing their ends, substantially as set forth.

In testimony whereof I have signed this specification in the presence of two subscribing witnesses.

PHILIP LINDEMAYER.
